UNITED STATES PATENT OFFICE.

FELIX EBERHART, OF NEWARK, NEW JERSEY, ASSIGNOR TO AMERICAN CAN COMPANY, OF NEW YORK, N. Y., A CORPORATION OF NEW JERSEY.

TALCUM-POWDER BOX.

1,340,217.

Specification of Letters Patent.

Patented May 18, 1920.

Application filed April 30, 1915. Serial No. 24,861.

To all whom it may concern:

Be it known that I, FELIX EBERHART, a citizen of the United States, residing in Newark, in the county of Essex and State of New Jersey, have invented a new and useful Improvement in Talcum-Powder Boxes, of which the following is a specification.

My invention relates in general to talcum powder boxes or containers and has for its object broadly the provision of an improved form of talcum powder box or container particularly adapted for carrying in the pocket or a hand bag, vanity case or the like, although it will be manifest that certain features of the invention have a much wider and more general application.

A principal object of the invention is the provision of a talcum powder box with a sifter device or opening so constructed and arranged that it will not extend beyond the side of the box.

A further object of the invention is the provision of such a container wherein the movable part of the sifter device will be enclosed within the immovable or stationary part in order that it may be protected from distortion and inadvertent movement from closed to open position.

A further object of the invention is the provision of such a construction which will be easily operable, pleasing in appearance and of economic construction.

A still further object of the invention is the provision of a container for talcum powder and the like from which the powder may be forcibly ejected, thereby preventing clogging of the sifter openings and insuring a ready delivery of powder without the necessity of violently shaking the container to cause its delivery.

Other objects and advantages of the invention will be apparent as it is better understood from the following description when considered in connection with the accompanying drawing illustrating a preferred embodiment thereof.

Referring to the drawing,

Figure 1 is a top plan view of a talcum powder container embodying my invention; Fig. 2 is a section on the line 2—2 of Fig. 1;

Fig. 3 is an end view looking toward the left in Fig. 2; and

Fig. 4 is a section taken on the line 4—4 of Fig. 2.

55

For the purpose of illustrating my invention I have shown it embodied in a talcum powder box 5 having a sifter device 6 and an ejecting device 7. On the drawing the container 5 is shown to be of flat, rectangular form, and although this is desirable if the talcum powder box is to be carried in the pocket, hand bag, vanity case or the like, it is by no means essential to my invention. In one of the ends of the container an aperture 8 is formed and in this aperture is secured the shifting device. This device in the present instance consists of a stationary part 9 crimped at its edges 10 about the edge 11 surrounding the aperture 8 so as to form interior and exterior peripheral shoulders engaging both within and without the edge of said aperture. The stationary member 9 extends inwardly into the box and is provided at its base with a series of sifter openings 12. The movable part 13 of the sifter device is of shape similar to the part 9 and also has openings or perforations 14 in it which are adapted to register with the openings 12 when it is desired to deliver powder 80 from the container. Like the member 9, the member 13 also extends inwardly of the container, the two forming a chamber in which a thumb-piece 15 secured to the movable sifter member and adapted to turn it is located. The stationary member 9 forms a chamber in which is seated the movable member 13 and the member 13 forms a chamber in which is located the thumb-piece 15. The movable member and the thumb-piece are preferably held in place by engagement of the edge 16 of the movable member behind the crimped edge 17 of the stationary member.

When the parts are constructed and arranged as just described, it will be manifest that the entire sifter device is located substantially in or behind the plane of the end wall 18 in which the sifter is provided. The movable member of the sifter device being inside the stationary member, is protected against distortion and the thumb-

piece being located inwardly of the side 18 is substantially protected from inadvertent movement from closed to open position.

In order that the powder may be forcibly ejected and in order also to eliminate the necessity of violently shaking the container to cause it to deliver powder, I provide in one of the broad faces 19 of the container a movable sheet 20 mounted in a recess 21 in this face. The edges 22 of this sheet are rigidly secured to the material of the wall 19 in any suitable fashion, in the present instance being shown as crimped therein at 23. The diameter of this sheet is somewhat larger than the opening, so that the sheet must either extend outwardly or inwardly in a curve. It is, however, of such material that it may be forced from one position to the other readily. A spring 24 is secured to the under face of the wall 19 by a rivet or other fastening means 25, and this spring bears against the sheet 20 holding it outwardly in the position shown in Fig. 2. If the sheet 20 however is pressed with the thumb of the person holding the container after the sifter has been opened, powder will be forced out through the reduction of the internal volume of the container.

It will be understood that the above described construction provides a non-refillable box, because the outer flange 10 may be bent outward and against the edge 11 after the box has been filled; or the box may be filled through an open side, the side shown at the bottom of Figs. 2 and 3, and thereafter the side member or cover double seamed in place as shown. In either way of filling the box it can not be refilled after the contents are exhausted.

The container and its attendant parts are of simple construction and pleasing in appearance, and it is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

I claim:

1. A container comprising an inwardly extending sifter member crimped at its edges to a side wall of said container, a sifter closure rotatably held in engagement with said sifter member and within said sifter member by the connection between said side wall and said sifter member.

2. A container for talcum powder having a plurality of discharge openings and a separate yielding member in its side and crimped therewith, means yieldingly press-
65 ing said member outwardly to increase the

internal volume of said container and adapted to be pressed inwardly to cause the powder to be forcibly ejected through said openings.

3. A container comprising a sheet metal box having an aperture in one of its walls; a stationary perforated sifting device joined by crimping with the edge of said aperture and extending inwardly into the body of the box, said crimping overhanging the interior portion of said sifting device; a movable closing part disposed within the stationary sifting device, the said movable part being held from outward displacement by the said overhanging crimping; and a thumb piece attached to the said movable part and located within the body of the box.

4. A container comprising a flat sheet metal box having an aperture in one of its narrow side walls; a stationary perforated sifting device crimped around the edges of said aperture and extending inwardly into the body of the box, said crimped portion overhanging the interior portion of said sifting device; a movable closing part disposed within the stationary sifting device, the said movable part being held from outward displacement by the said overhanging crimped portion of the sifting device; and a thumb piece attached to the said movable part and located within the body of the box.

5. A container comprising a flat sheet metal box having an aperture in one of its narrow walls and an aperture in one of its wide walls; a stationary perforated sifting device crimped around the edges of said aperture in the narrow wall and extending inwardly into the body of the box, said crimped portion overhanging the interior portion of said sifting device; a movable closing part disposed within the stationary sifting device, the said movable part being held from outward displacement by the said overhanging crimped portion of the sifting device; a thumb piece attached to the said movable part and located within the body of the box; a powder ejecting device in the form of a flexible plate around which the edge of said aperture in the wide wall is crimped; and a spring attached within the body of the box and bearing on the interior of the said powder-ejecting device.

6. A container comprising a flat sheet metal box having a powder-delivering means in one of its narrow walls and an aperture in one of its wide walls; a powder-ejecting device in the form of a flexible plate around which the edge of the said aperture is crimped; and a spring attached within the body of the box and bearing on the interior of the said powder-ejecting device.

7. A container comprising a flat sheet metal box having a powder-delivering means in one of its narrow walls and an aperture in one of its wide walls; a powder-
130

ejecting device in the form of a flexible plate around which the edge of the said aperture is crimped, said crimping holding the plate normally in an outwardly bulged position; and a spring engaging the said plate and acting to force it outward.

8. A sheet metal powder box having an opening, a cup-shaped closure extending into the interior of the box through said opening and formed with a shoulder which bears against the interior surface of the box and with a shoulder which bears against the

exterior of the box, said closure being irreversibly secured in place by the said shoulders, and said closure being perforated, and 15 a perforated rotary member seated in said closure.

Signed in the presence of two subscribing witnesses.

FELIX EBERHART.
